US00D631316S

(12) **United States Design Patent**
Krumpe et al.

(10) **Patent No.:** **US D631,316 S**
(b4) **Date of Patent:** **** Jan. 25, 2011**

(54) **FASTENING TOOL**

(75) Inventors: **Geraint Krumpe**, Chicago, IL (US);
Michael Reedy, Chicago, IL (US);
Victor Hoernig, Lowell, IN (US);
Charles A. Patterson, Durango, CO (US);
Man Ki Yoo, Skokie, IL (US);
Emilie Williams-Romero, Chicago, IL (US);
Marcus Bosch, Chicago, IL (US);
Steven J. Mandel, New York, NY (US)

(73) Assignee: **Arrow Fastener Co., LLC**, Saddle Brook, NJ (US)

(**) Term: **14 Years**

(21) Appl. No.: **29/357,866**

(22) Filed: **Mar. 18, 2010**

(51) **LOC (9) Cl.** **08-05**

(52) **U.S. Cl.** **D8/69**

(58) **Field of Classification Search** D8/69;
81/57.11, 429, 464, 465, 466, 469, 489; 173/13,
173/169, 178, 213, 217; 227/8, 114, 120,
227/130, 136, 142; 310/50; 408/20, 124,
408/125, 234, 241 R; 451/358

See application file for complete search history.

(57) **CLAIM**

The ornamental design for a fastening tool, as shown and described.

DESCRIPTION

FIG. 1 is a perspective view thereof;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines are for illustrative purposes only and form no part of the claimed design.
